(57) **CLAIM**

The ornamental design for a holster for a gun, as shown and described.

DESCRIPTION

FIG. 1 is a rear, left, top perspective view of a first embodiment of a holster for a gun in accordance with my new design; FIG. 2 is a front, left, top perspective view of the holster for a gun of FIG. 1;

FIG. 3 is a front view of the holster for a gun of FIG. 1;

FIG. 4 is a left side view of the holster for a gun of FIG. 1;

FIG. 5 is a rear view of the holster for a gun of FIG. 1;

FIG. 6 is a right side view of the holster for a gun of FIG. 1;

FIG. 7 is a top view of the holster for a gun of FIG. 1; FIG. 8 is a bottom view of the holster for a gun of FIG. 1; and FIG. 9 is a rear, right, bottom perspective view of the holster for a gun of FIG. 1.

FIG. 10 is a rear, right top perspective view of a second embodiment of a holster for a gun in accordance with my new design;

FIG. 11 is a front, right, top perspective view of the holster for a gun of FIG. 10;

FIG. 12 is a front view of the holster for a gun of FIG. 10;

FIG. 13 is a right side view of the holster for a gun of FIG. 10;

FIG. 14 is a rear view of the holster for a gun of FIG. 10;

FIG. 15 is a right side view of the holster for a gun of FIG. 10;

FIG. 16 is a top view of the holster for a gun of FIG. 10;

FIG. 17 is a bottom view of the holster for a gun of FIG. 10;

FIG. 18 is a rear, left, bottom perspective view of the holster for a gun of FIG. 10;

FIG. 19 is a rear, left, top perspective view of a third embodiment of a holster for a gun in accordance with my new design; FIG. 20 is a front, left, top perspective view of the holster for a gun of FIG. 19;

FIG. 21 is a front view of the holster for a gun of FIG. 19;

FIG. 22 is a left side view of the holster for a gun of FIG. 19;

FIG. 23 is a rear view of the holster for a gun of FIG. 19;

FIG. 24 is a right side view of the holster for a gun of FIG. 19;

FIG. 25 is a top view of the holster for a gun of FIG. 19;

FIG. 26 is a bottom view of the holster for a gun of FIG. 19; and

FIG. 27 is a rear, right, bottom perspective view of the holster for a gun of FIG. 19;

FIG. 28 is a rear, right top perspective view of a fourth embodiment of a holster for a gun in accordance with my new design;

FIG. 29 is a front, right, top perspective view of the holster for a gun of FIG. 28;

FIG. 30 is a front view of the holster for a gun of FIG. 28;

FIG. 31 is a right side view of the holster for a gun of FIG. 28;

FIG. 32 is a rear view of the holster for a gun of FIG. 28;

FIG. 33 is a right side view of the holster for a gun of FIG. 28;

FIG. 34 is a top view of the holster for a gun of FIG. 28;

FIG. 35 is a bottom view of the holster for a gun of FIG. 28; and,

FIG. 36 is a rear, left, bottom perspective view of the holster for a gun of FIG. 28.

All portions shown in broken lines are environmental and illustrative only and form no part of the claimed design.
